UNITED STATES PATENT OFFICE.

WILLIAM H. STEINBRECHER, OF DETROIT, MICHIGAN.

SHIFTING SEAT FOR SLEIGHS.

SPECIFICATION forming part of Letters Patent No. 291,635, dated January 8, 1884.

Application filed September 3, 1883. (No model.)

To all whom it may concern:

Be it known that I, WILLIAM H. STEINBRECHER, of Detroit, county of Wayne, and State of Michigan, have invented a new and useful Improvement in Shifting Seats for Sleighs, of which the following is a specification.

The object of my invention is to so construct a cutter or sleigh that it may be either one or two seated, and will be simple, durable, and readily changed from a single to a double seated sleigh, as hereinafter set forth; and my present invention consists in the general construction of parts, as set forth in the following specification.

In order to aid others skilled in the art to which my invention belongs to make and use it, I will proceed to describe its construction and operation with reference to the several drawings forming a part of this specification, in which—

Figure 1 is a perspective view of my invention, when arranged for double seat. Fig. 2 is a rear elevation, partly in section, showing the construction and arrangement of the rear braces. Fig. 3 is a diagram section, showing the sleigh as arranged for single seat. Fig. 4 is a detached view of the seat jump-irons. Fig. 5 is a sectional perspective of the front seat as inverted or folded down. Fig. 6 is a detached view of the lower portion of the runner-braces.

In the drawings, Fig. 1, A represents the usual sleigh-bottom; B, the adjusting or jump seat; C, the front or folding seat; S, the side of the sleigh-box to which is attached the upright frame F, to which the seat C is hinged and supported, as clearly shown in Fig. 5. The hinges d are provided with a pintle, e', to which the bar P is pivoted. This bar is also pivoted to the movable brace-irons D. The lower end of these are pivoted to the frame F. (See Figs. 1 and 5.)

Attached to the hinges d is an L-shaped iron or extension, d', having a supporting-lug, d'', which is attached across the under portion of the seat C. Each end of this seat is provided with a folding L-shaped extension, a, pivoted to the seat by means of the L-shaped irons a', being adapted to fold upon the seat C, as shown in Fig. 1.

To remove the seat C, as shown in Fig. 1,

to the position shown in Figs. 3 and 5, the end portions, a, are folded toward each other. The seat C is then rocked back upon the hinges d, 55 which causes the seat to drop into the bottom of the box, as shown in Fig. 3, or the position of Fig. 5. As the seat is rocked back the bar P is drawn backward, thus drawing the reciprocating brace-irons D to a vertical position against 60 the frame F, as shown in Figs. 3 and 5, where they are out of the way; and when the seat is thrown forward to the position of Fig. 1 the lugs d' stop upon the projecting ends of the brace-irons D, which are thrown outward by 65 the pivoted bars P. When the seat C is in the position of Figs. 3 and 5, the rear seat, B, having the braces E folded, as hereinafter described, is carried up and forward by the curved jump-irons h, as shown in dotted lines of Fig. 70 1, and in Fig. 4 as thrown forward; by dotted lines when thrown back. The jump-irons are in pairs, being pivoted to the bottom of the sleigh-box and to the under side of the seat B. When the seat B is moved forward, it passes 75 over the folded seat C, its front edge meeting the top rail of the frame F, as shown in Fig. 3, thus making a single-seated cutter. When the seat B is thrown back, as in Fig. 1, it projects over the sleigh-box, and to properly support it in this position I employ two 80 hollow metal braces, E. (See Figs. 1 and 2.) These braces are pivoted to lugs n n, attached to a suitable transverse bar, R, which is secured to the under side of the seat B, as 85 shown in Fig. 2. Near the center of this bar I attach two lugs, r r, connecting them with the hollow braces E by two jointed braces, a''. The braces E, from the point Y to the top, are slotted, for the purposes hereinafter set forth. 90 The lower end portion of the braces E are provided with a square opening, l. A slot is cut through the braces, in which the pin O slides. These pins pass through a bolt within the braces, and are pressed down by coil-springs 95 Z, as shown in Fig. 2. Passing from the cutter-body down upon the runners are two braces, b. (See Figs. 1 and 6.) The lower portion of these braces is provided with an offset having a hole, e, passing vertically through 100 it. (See Fig. 6.) When the braces E are in a vertical position, to support the seat B, as in Fig. 1, the square opening l, at the lower end of the braces E, receives the offset containing

the hole *e* of the braces *b*. The pin *O* being raised draws the internal bolt within the brace *E*, and when the braces are in position the coil-spring *Z* forces the internal bolt down through the hole *e* of the runner-brace, thus locking the parts together. The jointed braces *a*² are then forced down at the center, thus locking laterally the parts to the seat *B*. To move the seat forward, as in Fig. 3, the pins *O* are raised and the braces *a*² are thrown up at the center, when the braces *E* are swung up under the seat-bottom, as shown at the right hand of Fig. 2. The lower section of the braces *a*² fold within the longitudinal slots formed in the braces *E*, before mentioned, as the lower ends of the braces *E* pass upward. The projecting ends of the bolts at the end of the braces are caused to spring into the holes of the guards *x x*, attached to the lugs *n n*, as clearly shown in Fig. 2. In this position they are held parallel with the bottom of the seat *B*, when said seat may be readily moved forward, as hereinbefore mentioned.

Having thus described my invention in the most exact terms that I can give, what I claim as new, and desire to secure by Letters Patent, is—

1. In a sleigh-seat, the seat *C*, having hinged L-shaped end portions, said seat being secured to the frame *F* by hinges *d d*, said hinges hav-

ing L-shaped extensions *d'*, with lugs *d*² and pintles *e'*, connecting bars *P*, reciprocating braces *D*, said braces pivoted to the frame *F*, the whole when arranged and combined substantially as specified. 35

2. The combination of the seat *B*, having jump-irons *h* pivoted thereto, the hollow braces *E*, pivoted to the lugs *n*, said braces containing pins *O*, coil-springs *Z*, internal bolts, and square openings *l*, said openings and internal bolts engaging with the offset and holes *e* of the runner-braces *b*, as and for the purposes set forth. 40

3. The combination of the seat *B*, having the rail *R* attached thereto, the hollow braces *E*, pivoted to the lugs *n n*, with jointed braces *a*², pivoted at *Y*, and to the lugs *r*, the lower portion of the braces *a*², adapted to fold within the longitudinal openings of the braces *E*, substantially as and for the purposes set forth. 45

4. In a sleigh, the seat *B*, having the jump-irons *h* attached thereto, the seat adapted to move backward over the sleigh-box, and supported by folding brace-irons attached thereto and to the runner-braces, as specified. 50

WILLIAM H. STEINBRECHER.
